UNITED STATES PATENT OFFICE.

ARTHUR K. BRAKE, OF BUCKHANNON, WEST VIRGINIA.

HYDRANT OR WATER-PLUG.

SPECIFICATION forming part of Letters Patent No. 783,925, dated February 28, 1905.

Application filed December 8, 1903. Serial No. 184,323.

To all whom it may concern:

Be it known that I, ARTHUR K. BRAKE, a citizen of the United States, residing at Buckhannon, in the county of Upshur and State of West Virginia, have invented a new and useful Hydrant or Water-Plug, of which the following is a specification.

This invention relates to hydrants or water-plugs of the type distributed through cities in different locations for the attachment of hose for extinguishing fires; but the principles thereof may be embodied in hydrants of small dimensions for use on private grounds and in buildings.

The principal object of the invention is to provide an improved hydrant or water-plug of such construction that the attachment of the hose thereto may be effected in the shortest possible time and the ill effects of delay in bringing the stream of water to bear upon the fire diminished as much as possible.

Another important object of the invention is to provide an improved hydrant or water-plug so constructed that the operation of the mechanism for securing the hose to the hydrant will also effect the opening of the valve of the hydrant to allow the stream of water to pass through the hose.

A further object of the invention is to provide a form of hydrant or water-plug embodying several spigots, each having a separate valve and operating means therefor and improved means for locking the several valves simultaneously, so that the valves cannot be opened by persons bent on mischief and so that the release of all the valves when it is necessary to attach the fire-hose may be simultaneously effected.

In the attainment of the objects above stated I make use of the mechanism hereinafter disclosed, reference being had to the accompanying drawings, in which are illustrated several different forms of apparatus, each constructed in accord with the spirit of this invention, it being understood that changes in the form, proportions, and exact mode of assemblage of the elements exhibited may be resorted to without departing from the spirit of the invention or sacrificing the advantages thereof.

In the drawings, Figure 1 is a front eleva-

tion of one form of the invention. Fig. 2 is a vertical section through the form of the invention illustrated in Fig. 1, the hose being attached. Fig. 3 is a top view of the apparatus shown in Fig. 1. Fig. 4 is a detail view 55 in perspective of the rotatable sleeve. Fig. 5 is a detail view in perspective of the coupling member secured to the hose. Fig. 6 is a front elevation of a modified form of the invention. Fig. 7 is a vertical section through 60 the apparatus shown in Fig. 6, the hose being attached. Fig. 8 is a horizontal section through the spigot of the apparatus shown in Fig. 6, with the cover in position over the spigot. Fig. 9 is a detail view in perspective 65 of the rotatable operating member. Fig. 10 is a detail view in perspective of the sliding sleeve. Fig. 11 is a sectional view of the spigot in the form of the invention illustrated in Fig. 1, with the cap fitted thereon. Fig. 70 12 is a perspective view of the cap shown in Fig. 11, part being broken away to show the internal construction. Fig. 13 is a view, partly in side elevation and partly in section, of the upper portion of a modified form of the invention, the hose being attached. Fig. 14 is a top plan view of the modified form of the invention comprising a plurality of stocks and spigots.

Corresponding parts are designated by similar characters of reference throughout the several figures of the drawings.

Referring to the drawings, and more particularly to Figs. 1 and 2, S represents the stock of a fire-hydrant or water-plug having a central vertical bore 1 and a laterally-threaded aperture 2, in which is secured a spigot 3. The spigot 3 is held tightly in the aperture provided therefor in the stock of the hydrant, and the portion which projects from the stock 85 is preferably provided on the exterior with spiral grooves 4, in which move inwardly-disposed studs 5 in the interior of a sleeve 6, which is fitted loosely upon the spigot 3. The sleeve 6 has rigidly attached thereto a handle-lever 7, by means of which the sleeve is turned on the spigot, and at the inner end of the sleeve there is provided a cam 8, whose utility will presently be explained. The spigot 3 has 90 in the outer end thereof a conical chamber 9. 95 100

terminating at a shoulder 10, formed in the interior of the chamber and preferably covered by a washer 11, of rubber or other suitable material. The conical chamber 9 is provided for the reception of the correspondingly-formed extremity of a coupling member 12, secured in the end of the hose to be attached to the hydrant, and the means for securing the member 12 in the chamber 9 consists of a pair of segmental flanges 13, provided on the outer end of the sleeve 6, and a pair of curved lugs 14, suitably placed upon the coupling member 12, carried by the hose. Each of the segmental flanges 13 is spaced from the end of the sleeve 6 to a sufficient extent to permit the ready passage of one of the lugs 14 between the flange and the end of the sleeve, and the movement of the lugs 14 between the flanges 13 and the end of the sleeve is limited by stops 15 at opposite ends of the flanges.

When the hydrant is not in use, the chamber in the outer end of the spigot is preferably covered by a cap 16, which fits over the outer end of the sleeve 6 and is effective to prevent the entrance of trash or other obstructive material into the spigot. The cap 16 is preferably provided on the interior with two projecting guides 17, upon which is slidably mounted a disk 18, whose diameter is approximately equal to the diameter of the outer end of the spigot 3. The disk 18 is held normally at the ends of the guide-rods 17 by means of a coiled spring 19, disposed between the disk 18 and the cap 16; but when the cap is in position upon the end of the sleeve 6 the spring 19 is compressed and the disk 18 is forced back into the cap by the outer end of the spigot. To hold the cap in position on the end of the sleeve, oppositely-disposed spring-catches 20 are arranged in the cap adjacent to the periphery thereof and are adapted to engage with the flanges 13 on the outer end of the sleeve 6. In order to secure the cap on the end of the sleeve 6, the guide-rods 17 are introduced into grooves 21 in the outer surface of the spigot and the sleeve 6 is then given a turn in the direction indicated by the arrow X. This movement brings the spring-catches 20 into engagement with the flanges 13, and as the rods 17 are held in the grooves 21 on the outside of the spigot release of the cap is impossible until the sleeve is restored to its original position.

The valve mechanism consists of any preferred form of valve, as the tapered plug 22, provided in the lower end of the stock, and the operating devices now to be described. A rod 23 extends upward through the bore of the stock and passes through a suitably-packed opening in the top. At its upper end the rod 23 is threaded for engagement with a lug 24 on a sliding frame 25, which is arranged in suitable guides on the stock of the hydrant. By turning the valve-plug and the rod associated therewith the rod may be ad-

justed in the lug 24 to any desired position. The frame 25 may be of any suitable form, but must present surfaces 26 and 27 for engagement with the cam 8 on the sleeve 6. When the cam is in engagement with the surface 26, the frame 25 is held in raised position and the valve at the bottom of the stock is closed. When the sleeve 6 is turned and the cam 8 is brought into engagement with the surface 27 by movement in the direction indicated by the arrow X, the frame 25 will be depressed and the valve at the bottom of the stock will be opened.

In order to prevent the turning of the sleeve and opening of the valve by unauthorized persons, a pivoted member 28 is mounted on top of the stock of the hydrant, and a latch-pin 29, pivotally connected with the member 28, is arranged for sliding movement in a guide 30. The latch-pin 29 is adapted to enter an aperture 31, provided on the inner surface of the cam 8 at such a point that when the latch-pin engages with the aperture the handle-lever 7, by which the sleeve 6 and the cam 8 are moved, will be held in substantially vertical position, as shown in Fig. 1. The pivoted member 28 is secured in position to hold the latch-pin in engagement with the cam by means of a padlock 32 engaging eyes 33 and 34 on the stock S and the member 28, respectively.

When it is desired to attach the hose to the hydrant above described, the padlock 32 must be unlocked and removed from the eyes 33 and 34. The pivoted member 28 is then turned on its pivot to withdraw the latch-pin 29 from the aperture in the cam, and the handle-lever is then free to move. The handle-lever is next swung in the direction indicated by the arrow Y until the cover of the spigot is released. The coupling member 12 is then thrust into the chamber 9 in the outer end of the spigot until the lugs 14 contact with the end of the sleeve 6, when the handle-lever is turned in the direction indicated by the arrow X, and the inward movement of the sleeve 6 on the spigot 3 brings the flanges 13 into engagement with the lugs 14 on the coupling member and forces said coupling member into close contact with the wall of the chamber 9 and the washer 11 in the bottom thereof. The same movement of the handle-lever causes the cam 8 to pass out of engagement with the surface 26 on the frame 25 and into engagement with the surface 27. The frame 25 is consequently depressed, and the valve at the bottom of the stock of the hydrant is opened as soon as the hose is securely held in the spigot.

From the foregoing description and the drawings illustrative thereof it will be readily seen that the entire operation of unlocking the hydrant, securing the hose in position thereon, and opening the valve to permit the flow of water through the hose may be ac-

complished in a very few seconds. It will also be noticed that the opening of the valve and the attachment of the hose to the spigot are effected by the use of a lever upon which a considerable amount of force may be brought to bear, so insuring close contact of the coupling member at the end of the hose with the chamber in the spigot and the opening of the valve even though bound by corrosion or jammed into its seat.

In Figs. 6 and 7 I have shown another form of embodiment of the invention, in which the spigot 3 is replaced by a spigot 40, the projecting portion of which is square in cross-section at its outer end and circular in cross-section at its inner end. On the circular portion of the spigot 40 is mounted a cam-plate 41, which takes the place of the cam 8, already mentioned. The cam-plate 41 bears a lever 42, by means of which the cam is operated, and a ring 43, having oppositely-disposed forwardly-projecting lugs 44, which engage with the thread 45 on the exterior of a member 46, slidably mounted on the square portion 25 of the spigot 40. The member 46 is disk-like in form and has a square central opening through which the spigot 40 projects. A square sleeve 47 is attached to the outer face of the member 46 and surrounds the spigot, 30 being spaced therefrom sufficiently to form a housing for clamping members 48 of the form shown in Fig. 6. Each of the clamping members 48 consists of a bent rod the terminals of which are secured in eyes 49 on the member 46 and arranged for sliding movement in eyes 50 on the spigot 40. The members 48 are curved intermediate of their ends, as shown at 51, and are adapted for engagement with a coupling member 52, secured in the 35 end of the hose. The coupling member 52 has a conical end for engagement with a conical chamber 53 in the outer end of the spigot and is provided with circumferential flanges 54, between which the clamping members 48 are adapted to enter.

The valve and operating mechanism are similar to those already described, and separate description is therefore unnecessary.

A cap 55 is preferably hinged to the sleeve 50 on the under side thereof, and a fastening device consisting of a resilient loop 56 of greater width than length is provided on the inner surface of the cap.

When the lever 42 is in vertical position, the 55 clamping members 48 will engage with the sides of the resilient loop and hold the cap in contact with the end of the sleeve 47. When, however, the lever 42 is moved in the direction indicated by the arrow Y, the clamping members 48 will be separated, and the resiliency of the loop 56 will operate to throw the cap outward from its position over the end of the sleeve 47, thus exposing the end of the spigot and permitting the introduction of the 60 coupling member 52 thereinto.

In the operation of the modified form of the invention the unlocking of the mechanism is effected in the manner already described, and the coupling member 52 is secured in the spigot by being introduced into the chamber 75 53 when the operating-lever is in vertical position and the clamping members 48 are spread apart sufficiently to permit the introduction of the member 52 between them. When the coupling member has been fitted in 75 the chamber 53, the lever 42 is moved in the direction indicated by the arrow X, and the lugs 44 engaging with the threads 45 of the member 46 force said member 46 inward, and the members 48 attached thereto are drawn 80 together and also drawn inward, so being brought into engagement with the flange 54 and forcing the member 52 into close contact with the interior of the chamber 53 and the washer 53' in the bottom thereof. 85

In Fig. 13 there is illustrated another embodiment of the invention, which is especially designed for use with a hose having a female coupling member. In this modification of the invention a spigot 60 is provided 90 on the interior with spiral grooves 61, and a sleeve 62, having inwardly-disposed studs 63 engaging the grooves 61, is rotatably mounted on the spigot, as shown. The sleeve 62 is provided with notches 64 in the outer end thereof, 95 which are formed obliquely and are substantially at right angles to the grooves 61 on the spigot. The spigot is tapered at the outer end, as shown, and is adapted to enter a chamber 65 in a female coupling member 66, secured 100 in the end of the hose. The coupling member 66 has on the end thereof a plurality of obliquely-disposed teeth 67, adapted to enter the notches in the outer end of the sleeve 62.

To secure the female coupling member upon 105 the spigot, the teeth 67 are brought into engagement with the notches 64 on the sleeve 62, and the sleeve is then turned upon the spigot in the direction indicated by the arrow X, a handle-lever 68 being provided on 110 the sleeve in order to turn it in the desired direction. The rotation of the sleeve on the spigot causes it to be forced inward by the travel of the studs 63 in the spiral grooves 61, and the same movement of the sleeve forces 115 the teeth 67 into closer engagement with the notches 64 and also causes the coupling member 66 to be drawn into close contact with the end of the spigot. In this operation the opening of the valve is effected by means of a cam 69, carried by the sleeve 62, which engages with the sliding frame 25 in the same manner that the cam 8 does.

When it is desired to combine in a single plug a plurality of spigots in order that several lines of hose may be supplied from the same point, a mechanism of the form illustrated in Fig. 14 may be employed. In this form of the invention four separate stocks are shown grouped about a central vertical shaft 125 130

or post 70, the spigots of the several stocks being disposed outward, as shown. The spigots and hose securing devices may be of any of the forms already described, and specific illustration thereof is unnecessary. In this form of the invention, however, each of the spigots will be provided with a cam 71, provided its inner surface with a plurality of cogs 72 for engagement with a series of cogs suitably placed upon the periphery of a wheel 73, which is mounted for rotation in a horizontal plane upon the shaft or post 70. The wheel 73 is secured upon the shaft 70 in any suitable manner and is provided with a spiral spring 74, which tends to turn the wheel in the direction shown by the arrow Z. The movement of the wheel in the direction indicated is limited by a stop 75, provided upon one of the stocks S, and in order to move the wheel in the opposite direction a handle 76 is mounted on a spoke of the wheel at any convenient point. When the wheel is in the position shown in solid lines in Fig. 14 and the cogs are in engagement with the cogs 72 of the cams 71, all of said cams will be held in position to keep the valves in the stocks closed and to hold the caps over the ends of the spigots. To retain the wheel in this position, a lock 77 is secured in an eye 78 upon one of the stocks and an eye 79 provided upon one of the spokes of wheel at a suitable distance from the center.

When it is desired to release the cams 71, so that the valves may be opened and water supplied to one or more lines of hose, the lock 77 must be removed from the eyes 78 and 79, and the spring 73 will then act to turn the wheel in the direction indicated by the arrow Z and move the cams 71 in the direction to effect the release of the caps from the spigots. The mechanisms connected with the several stocks having been released, the attachment of each line of hose and the opening of the valve to supply water thereto is effected in one of the ways already explained.

While the invention has been described as embodied in a special form of hydrant, it will be readily seen that the devices employed for securing the hose in position may be applied to an ordinary water-plug or hydrant by merely securing a spigot of any one of the forms shown in a spigot of the water-plug; but the valve-operating means shown in the forms of the invention described will not then be susceptible of use unless some form of connection between the handle-lever and the valve-rod be provided especially for use under such circumstances. When a spigot of one of the forms shown is applied to an ordinary water-plug, the handle-lever provided on the spigot will be employed to operate the hose-securing devices; but the valve will preferably be operated by the ordinary devices provided for that purpose.

It is to be understood that the several forms

of the invention shown and described constitute merely the preferred forms of embodiment thereof, and various changes in the details of construction, both as to the form of the members and their mode of arrangement, may be resorted to without departing from the spirit of the invention or sacrificing its advantages. I do not, therefore, limit myself specifically to the form shown, but reserve the right to make such changes therein as fall within the scope of the appended claims.

Having thus described the construction and operation of my invention, what I claim as new, and desire to secure by Letters Patent, is—

1. In a hydrant, a spigot threaded into the same and having an extended portion with exterior threaded grooves, a sleeve having lugs engaging said grooves, said sleeve being provided with flanged extensions at its outer end and a stop at one end of each of said flanges, said stops being diametrically opposite, and a hose-carrying member having opposite flanges to engage the flanged extensions of the movable sleeve.

2. The combination in a hydrant, of a valve, a hose-receiving member separated from said valve, a hose-securing member carried by said hose-receiving member and movable relatively thereto, and means for simultaneously operating said valve and said hose-securing member.

3. The combination in a hydrant, of a valve, a hose-receiving member, a hose-securing member mounted upon said hose-receiving member and movable relatively thereto, a member connected with said valve and movable transversely of said hose-receiving member, and means for simultaneously operating said hose-securing member and imparting movement to said shiftable member to operate the valve.

4. The combination in a hydrant, of a stock, a valve, a frame slidably mounted on said stock and connected with the valve, a hose-receiving member mounted on said stock, hose-securing means carried by the hose-receiving member, and means for operating said hose-securing means, said operating means including a cam adapted for engagement with said frame to impart movement thereto to open or close said valve.

5. The combination in a hydrant, of a stock, a hose-receiving member mounted on said stock, hose-securing devices rotatably mounted on said hose-receiving member and comprising a cam, a valve, a frame slidably mounted on said stock and adjustably connected with said valve, said frame having surfaces adapted for engagement with said cam, and means for rotating said hose-securing devices and thereby to bring said cam into engagement with the surfaces on said frame adapted for engagement therewith.

6. The combination in a hydrant, of a hose-receiving member, hose-securing means, a cover for said hose-receiving member, and fastening devices provided on said hose-securing means for engaging said cover and securing it in position over said hose-receiving member.
7. The combination in a hydrant, of a hose-receiving member, hose-securing devices mounted on said hose-receiving member, a cover for said hose-receiving member, catches provided on said cover, and devices provided on said hose-securing means for engagement with said catches.
8. The combination in a hydrant, of hose-securing means, a valve, single means for operating the hose-securing means and said valve, and a lock for said operating means whereby the operation of said valve and said hose-securing means are both prevented.
9. The combination in a hydrant, of a stock, a valve, valve-operating means supported by said stock and comprising a rotary cam, and locking devices mounted on said stock and adapted for engagement with said cam.
10. The combination in a hydrant, of a stock, a valve, a valve-rod extending upward through said stock, a frame slidably mounted on said stock and having a projecting lug in threaded engagement with said valve-rod, and valve-operating means comprising a rotary cam adapted for engagement with said frame to impart sliding movement thereto so as to open or close the valve.
11. The combination in a hydrant, of a stock, a valve in said stock, valve-operating mechanism comprising a rotary member supported by said stock at one side thereof, said rotary member having a latch-receiving opening, a pivoted latch member mounted on top of said stock and adapted for engagement with said opening, and means for locking said latch member in engagement with said opening.
12. The combination in a hydrant, of a plurality of stocks, valve-operating mechanism associated with each stock, and means for simultaneously locking all of said valve-operating mechanisms.
13. The combination in a hydrant, of a plurality of stocks, valve-operating mechanism associated with each stock, each valve-operating mechanism comprising a rotary member provided with cogs, and single means for locking all of said valve-operating mechanisms comprising a wheel having cogs adapted for engagement with the cogs of all of said rotary members, and a lock for said wheel.
14. The combination in a hydrant, of a plurality of stocks, valve-operating mechanism associated with each stock, each valve-operating mechanism comprising a rotary member provided with cogs, means for locking all of said valve-operating mechanisms comprising a wheel having cogs adapted to engage with the cogs of all of said rotary members, a lock for said wheel, and a spring adapted to turn said wheel to throw the cogs thereon out of engagement with the cogs of said rotary members as soon as said lock is released.
- In testimony that I claim the foregoing as my own I have hereto affixed my signature in the presence of two witnesses.

ARTHUR K. BRAKE.
